CHARLES I. GOLDBLATT

BY Munn Co.

ATTORNEYS

UNITED STATES PATENT OFFICE.

CHARLES I. GOLDBLATT, OF BROOKLYN, NEW YORK.

WINDOW-OPERATING DEVICE.

1,421,938.

Specification of Letters Patent. Patented July 4, 1922.

Application filed March 10, 1921. Serial No. 451,186.

To all whom it may concern:

Be it known that I, CHARLES ISRAEL GOLDBLATT, a citizen of the United States, and a resident of the city of New York, borough 5 of Brooklyn, in the county of Kings and State of New York, have invented a new and Improved Window-Operating Device, of which the following is a full, clear, and exact description.

10 This invention relates to improvements in window operating devices, an object of the invention being to provide an apparatus which will entirely obviate the necessity of manually raising or lowering window sashes.

15 A further object of the invention is to provide a novel form of hydraulic mechanism for raising or lowering window sashes.

20 A still further object is to provide an operating mechanism, which will be simple and practical in construction, durable and efficient in use, and to suggest one practical method of applying the apparatus to a conventional form of window sash.

25 With these and other objects in view, the invention consists in certain novel features of construction and combinations and arrangements of parts as will be more fully hereinafter described and pointed out in the claims.

30 In the accompanying drawings:—

Figure 1 is a somewhat diagrammatic view in front elevation with parts broken away for clearness, illustrating my improved operating mechanism in applied position;

35 Figure 2 is a view in section on the line 2—2 of Figure 1; and

Figure 3 is a sectional detail view of one of the operating valves.

40 Referring more specifically to the drawings, 1 represents a window frame, in which an upper sash member 2 and a lower sash member 3 are slideable vertically one behind the other.

45 The side members 4 of the frame 1 are preferably hollow and each of these members accommodates a pair of tanks such as 5 and 5' respectively, extending from the top to the bottom of the members. In the upper ends of the tanks 5, pulleys 6 are 50 mounted and flexible devices 7 are operatively connected at one end to the lower sash 3 and run over the pulleys. Counterweights 8 are suspended on the other ends of the flexible devices 7 and are located in the 55 tanks 5.

9 represents a water supply pipe and 10 a valve, controlling the flow of water through the pipe 9. The pipe 9 is connected with any suitable source of supply (not shown).

Branch supply pipes 12 lead from the supply pipe 9 and communicate with the lower ends of the tanks 5. A main outlet pipe 13 is connected by branch pipes 14 to the lower ends of the tanks 5. Flow through the outlet pipe is controlled by a valve 15 similar to the valve 10. Over-flow pipes 16' communicating with the upper ends of the tanks 5 empty into the pipe 13 below the valve 15.

The theory of operation is as follows:—

70 The weights or counterbalances 8 are together heavy enough to overcome the weight of the sash 3 and the friction between the sash and its frame, so that when the tanks 5 are empty, the counterbalances 8 will rest on the bottom of the tanks and hold the sash 75 3 in elevated position. It is a well recognized principle, however, that a body immersed in fluid loses an amount of weight equal to that of the fluid which it displaces. The weights 8, therefore, while sufficiently 80 heavy to normally retain the sash in its elevated position, will quickly cease to be effective when the tanks are flooded to partially immerse them, and when the tanks 5 are flooded by opening the valve 10, the sash 85 will descend to the position illustrated in the drawings. In other words, when the tanks 5 are empty, operation of the valve 10 will lower the sash and when the sash is in lowered position, operation of the valve 15 will 90 raise it to any desired height.

95 The upper sash 2 is operated on the same principle. Pulleys 16 are mounted in the upper ends of the tanks 5'. Flexible devices 17 are operatively connected at one end to the upper sash 2 and are run over the pulleys 16. Counterbalances 18 are suspended on the free ends of the flexible devices 17 and are located in the tanks 5'. 19 represents a water supply pipe controlled by a valve 100 20 and connected by branch pipes 21 with the lower ends of the tanks 5'. A main outlet pipe 22 is controlled by a valve 23. Outlet pipes 24 leading from the lower ends of the tanks 5' communicate with the pipe 22 105 above the valve 23 and a pair of over-flow pipes 25 are provided and likewise communicate with the main outlet pipe 22.

110 In this instance, the upper sash is retained in its normal elevated position when the

tanks 5' are empty and flooding of these tanks will cause the sash 2 to fall by gravity to any desired position.

Very obviously, the particular construction of the valves 10, 15, 20 and 23 is immaterial to this invention. All of these valves are similar in construction and I have shown in Figure 3, the details of construction of the valve 10 merely for the purpose of illustrating one form of valve, which will perform the desired function.

In this figure, 26 represents a valve casing located in the pipe 9. A partition 27 is provided across the valve casing and is formed with a valve seat 28. A spring held poppet valve controlling the flow of water through the pipe 9 is normally retained in position on the seat by a spring 30 around the valve stem 31. The stem 31 is appreciably elongated and terminates in a push button or other handle member such as 32, for operating the stem, to permit a flow through the pipe 9.

In installing my improved apparatus, the various inlet and outlet pipes will be concealed in a wall, so that only the push buttons for operating the valves are visible, as seen in Figure 2.

I have illustrated one of the preferred embodiments of my invention. Obviously various slight changes and alterations might be made in the general form and arrangement of the parts described and hence I do not wish to limit myself to the precise details set forth, but shall consider myself at liberty to make such slight changes and alterations as fairly fall within the spirit and scope of the appended claims.

I claim:

- 40 1. The combination with a frame and a member slideable vertically in the frame, of a counterbalance normally retaining said member in elevated position, a flexible device connecting the slideable member and the counterweight, and means for partially immersing the counterbalance in a fluid, whereby the weight of the sliding member will preponderate and said member will slide by gravity in the frame.
- 50 2. The combination with a closure frame and a closure slideable vertically in the frame, of a tank, a flexible device operatively con-

nected at one end to the closure, a counterbalance located in the tank and suspended on the other end of the flexible device, and means for introducing fluid into the tank to reduce the weight of the counterbalance and permit the closure to descend by gravity.

55 3. The combination with a window frame and a sash slideable vertically in the frame, of a tank located on each side of the frame, pulleys mounted in the upper ends of the tanks, flexible devices having their intermediate portions located over the pulleys and operatively connected at one end to the sash, counterbalances in the tanks suspended on the other ends of the flexible devices and normally retaining the sash in elevated position, fluid inlet and outlet pipes communicating with the tanks, valves controlling the flow of fluid through said pipes, and means whereby the introduction of fluid into the tanks will cause the sash to descend by gravity.

60 4. A device of the character described in claim 4, and including over-flow pipes communicating with the upper ends of the tanks.

65 5. The combination with a frame, of a pair of sashes slideable vertically in the frame, a pair of counterbalances operatively connected to each sash and tending to hold both of said sashes in elevated position, independent means for immersing either pair of counterbalances in a fluid, and means whereby the immersion of the counterbalances causes the sashes to which they are attached to descend by gravity.

70 6. The combination with a frame, of a pair of sashes slideable vertically in the frame, a pair of counterbalances operatively connected to each sash and tending to hold both of said sashes in elevated position, independent means for immersing either pair of counterbalances in a fluid, said means comprising tanks enclosing the counterbalances, inlet and outlet pipes communicating with the tanks, spring held valves controlling the flow of fluid through the pipes, push buttons for operating the valves, and means whereby the immersion of the counterbalances causes the sashes to which they are attached to gravitationally descend.

CHARLES I. GOLDBLATT.
